US0D1109743S

(12) **United States Design Patent** (10) Patent No.: **US D1,109,743 S**
(45) Date of Patent: ** Jan. 20, 2026

(54) **PROTECTIVE CASE FOR A TABLET**

(71) Applicant: **Electronic Silk Road (Shenzhen) Tech Co., Ltd.**, Shenzhen (CN)

(72) Inventor: **Yuchen Qiu**, Guangdong (CN)

(**) Term: **15 Years**

(21) Appl. No.: **35/524,108**

(22) Filed: **Jan. 24, 2025**

(80) **Hague Agreement Data**

Int. Filing Date: **Jan. 24, 2025**

Int. Reg. No.: **DM/244331**

Int. Reg. Date: **Jan. 24, 2025**

Int. Reg. Pub. Date: **Feb. 28, 2025**

(30) **Foreign Application Priority Data**

Jan. 15, 2025 (CN) 202530025932.0

(51) **LOC (15) Cl.** **14-02**

(52) **U.S. Cl.**

USPC **D14/440**

Primary Examiner — Cynthia R Underwood

(57) **CLAIM**

The ornamental design for a protective case for a tablet as shown and described.

DESCRIPTION

1. Protective case for a tablet

1.1: Front

1.2: Back

1.3: Left

1.4: Right

1.5: Top

1.6: Bottom

1.7: Perspective

1.8: Perspective

1.9: Perspective

1.10: Perspective

Reproduction 1.1 is a front view of a protective case for a tablet showing my new design; Reproduction 1.2 is a rear view thereof; Reproduction 1.3 is a left view thereof; Reproduction 1.4 is a right view thereof; Reproduction 1.5 is a top view thereof; Reproduction 1.6 is a bottom view thereof; Reproduction 1.7 is a front, top and left side perspective view thereof; Reproduction 1.8 is a front, bottom and right side perspective view thereof; Reproduction 1.9 is a rear, top and right side perspective view thereof; and Reproduction 1.10 is a rear, bottom and left side perspective view thereof.

1 Claim, 10 Drawing Sheets
